UNITED STATES PATENT OFFICE.

HAROLD J. BRADT, OF DETROIT, MICHIGAN.

DISK WHEEL.

Application filed December 5, 1923. Serial No. 678,625.

This invention relates to disk wheels and has special reference to that class of double disk vehicle wheels provided with demountable tire supporting rims.

5 My invention aims to provide a double disk wheel body wherein the center hub supporting portion of the body is firmly connected to a hub and the disks of the body braced to provide a rigid body portion at 10 the hub.

The disks are formed with annular inwardly bulged portions so that the bodies of the disks intersect the plane of rotation and the peripheries of said disks are formed 15 with flanges adapted for supporting a demountable rim. The disk flanges have a configuration which necessitates forcing a demountable rim inwardly on to the flanges and provision is made to prevent circumferential creeping of the demountable rim 20 on the flanges.

My invention further aims to provide a double disk wheel wherein the disks have rim supporting flanges with the peripheral 25 portions of the disks articulated by rim holding fasteners which may be easily and quickly placed in position to prevent an outward displacement of the tire supporting rim during rotation of the wheel.

30 My invention further aims to provide a disk vehicle wheel possessing the requisite degree of rigidity and at the same time affording a degree of resiliency which will contribute to safe and easy riding of a vehicle body supported by wheels in accordance with 35 this invention.

My invention further aims to provide a 40 wheel body composed of inner and outer disks having peripheral flanges with said flanges disposed so that the flange of the inner disk may be somewhat contracted or drawn into a rim, and the flange of the outer disk crowded on to the inner disk so that the flange of the outer disk is somewhat 45 spread and adapted to cooperate with the flange of the inner disk in clamping a rim or other structure on said disks.

My double disk wheel will be hereinafter 50 specifically described and then claimed, and reference will now be had to the drawings, wherein—

Figure 1 is an elevation of the outer side of a portion of a disk wheel in accordance with this invention;

Fig. 2 is a vertical cross sectional view 55 of the disk wheel;

Fig. 3 is a horizontal sectional view of a portion of the disk wheel showing a split rim;

Fig. 4 is a longitudinal sectional view of 60 a portion of the split rim;

Fig. 5 is a perspective view of the same;

Fig. 6 is a cross sectional view taken on the line VI—VI of Fig. 3;

Fig. 7 is a plan of a portion of a disk 65 flange;

Fig. 8 is a perspective view of the same;

Fig. 9 is an enlarged elevation of a rim fastener;

Fig. 10 is a detail sectional view of a portion of a rim and double disk body showing the flanges of the disks clamping the rim on the disk body, and

Fig. 11 is a similar view showing the relation between the rim and disk flanges. 75

The wheel body is composed of an outer disk 1 and an inner disk 2 and these disks have central portions disposed in parallelism and provided with co-axial flanged openings with the annular flanges 3 and 4 confronting each other so that said flanges may bear upon a hub 5 provided with a brake drum 6, a fixed inner plate or head 7 and a detachable outer plate or head 8.

Between the disks 1 and 2, at the hub 5 is 85 an annular filler member 9 having a wall 10 engaging the outer face of the inner disk 2 and a flange 11 engaging the inner face of the outer disk 1. The filler member 9 spaces the disks 1 and 2 apart and is adapted to 90 hold said disks against the heads 7 and 8 when said heads are connected by a plurality of nut equipped bolts 12 extending through said heads, the disks 1 and 2, the filler member 9 and the brake drum 6. 95

In addition to the filler member 9 bracing the inner wall of the outer disk 1, said filler member bears on the flange 3 of the outer disk 1 and braces said flange by reason of the bolts 12 extending through the filler member. It is preferable to have the periphery of the filler member 9 meet the inner face of the outer disk 1 adjacent the peripheral edges of the head 8 and in turn the outer flange 11 of the filler member so that the outer disk may flex without any shearing action at the head 8.

The inner and outer disks are provided

with annular inwardly bulged portions 13 which bring the disks into closer proximity to each other and imparts a compound curve, in cross section, to said disks, so that said 5 disks will intersect parallel planes of wheel rotation. With these disks bulged or dished a degree of resiliency is imparted to the same and clearance provided at the outer disk 1 for a pneumatic tire filling tube or 10 connection 14 which is adapted to extend through an opening 15 in the outer disk.

The periphery of the inner disk 2 terminates in an annular flange 16 and said flange is not exactly disposed at a right angle to 15 the plane of the disk 2, but is slightly at an angle to said disk so that the free edge of the flange 16 will have a diameter slightly greater than where the flange joins the disk. This is in order that a demountable rim 17 20 may be placed on the flange 16 and cause compression or flexure of the flange 16 as the rim 17 is forced inwardly with the binding action between the rim 17 and the flange 16 preventing excessive inward movement and 25 displacement of the rim 17 relative to the double disk body of the wheel. This is best shown in Figs. 10 and 11 where the flange 16 has its angularity exaggerated and if the flange is not retracted as fully as shown in 30 Fig. 2, then the rim 17 will contact with the edge of the flange 16 and obtain a firm purchase thereon. In drawing the inner disk into the rim or forcing the rim on to the flange 16, it may happen that the edges of 35 the flange 16 will protrude from the inner side of the rim and the rim stick and seat on the flange 16 some place between the outer edges of the flange and the body of the disk 13.

40 The outer disk 1 also has a peripheral flange 18 similar in many respects to the flange 16 but maintained in spaced relation to the flange 16 except at depressed portions 19 of said flange where extensions 20 abut 45 the disk 2 contiguous to the flange 16 thereof. The extensions 20 of the flange 18 may ride up on to the curved portion of the flange 16, at its juncture with the disk 13 and in so doing tend to distend the flange 18 whereby 50 it may cooperate with the flange 16 in clamping and supporting the rim 17. The rim 17 is of the split type having its split ends 21 transversely slotted, as at 22 and inwardly pressed to form seats 23 for a connecting bar 55 24 flush with the outer wall of the rim 17, and fixed to one end of the rim by rivets 25 and attached to the opposite end of the rim by a screw bolt 26. This manner of connecting the split ends of the rim permits of said 60 rim being easily mounted in an inflated pneumatic tire or outer casing 27 which has the filling tube or connection 24 extending through an opening 28 of the rim 17 and a notch or slot 29 in the flange 18. This flange 65 is also provided with a side notch or recess

30 into which extends the seat 23 of the rim 17, said seat establishing a connection between the flange 18 and the rim 17 which prevents circumferential creeping of the rim on the flanges 16 and 18.

The rim 17 is formed with an annular inwardly projecting bead 31 adjacent its outer clasher edge or flange 32, said bead abutting the outer disk 1 to limit the inward movement of the demountable rim 17 on the disk flanges 16 and 18, even though these flanges do not frictionally hold the demountable rim against inward movement the bead 31 will do so. The bead 31 is adapted to be engaged by fasteners comprising bead and disk engaging clips 33 provided with lips 34 extending between the bead 31 and the outer disk 1 to extend into the depressions 19 of the flange 18. The clips 33 may be held in position by nut equipped bolts 35 non-rotatably held by the disk 2 and extending through openings 36 of the outer disk 1 and through the clips 33 with nuts 27 on the outer ends of said bolts. After the rim is placed on the disks the fasteners 30 may be employed for drawing the flange 16 into the rim, causing distention of the flange 18, and firm anchoring of the rim on the disk body of the wheel.

It is thought that the manner of constructing the wheel and the advantages gained by such construction will be apparent without further description, and while in the drawings there is illustrated a preferred embodiment of my invention, it is to be understood that the structural elements are susceptible to such variations and modifications as fall within the scope of the appended claims.

What I claim is:—

1. In a disk wheel, a double disk body composed of inner and outer disks, peripheral flanges carried by said inner and outer disks and extending in the same direction relative to said disks, a demountable rim seated on the flanges of said disks, said flanges being in proximity to each other and having a combined width approximately the width of said rim, and rim fasteners carried by said inner and outer disks adjacent the flanges thereof.

2. A disk wheel as called for in claim 1, wherein said demountable rim has an annular bead adapted to abut the outer disk at the base of its flange which disk has its flange provided with depressed portions to receive portions of said rim fasteners.

3. A disk wheel as called for in claim 1, wherein said rim fasteners include clips adapted to engage between said rim and said outer disk and extend onto the flange of the outer disk.

4. In a disk wheel, a double disk body having peripheral flanges with the flange of one of said disks provided with a depressed portion, and a rim having an internal abut-

ment thereon, the depressed portion of said disk engaging the periphery of the other of said disks, whereby outward pressure of the depressed flange is exerted against the inner wall of said rim, said depressed portion also serving to receive said abutment and prevent circumferential creeping of said rim on said disks.

5. In a disk wheel, a rim, inner and outer disks having peripheral flanges adapted to clamp the inner wall of the rim, the flange of the inner disk being retracted when the rim is placed thereon, the flange of the outer disk being distended by abutting the inner disk, and means for connecting said disks to retain the rim on the flanges of said disks.

10. A disk wheel comprising a rim, inner and outer disks, and flanges on said disks engaging said rim, one of said flanges being distended by engagement with the other flange.

15. In a disk wheel, a rim, inner and outer

disks, flanges on said disks, one of said flanges adapted to be retracted and the other flange distended with both of said flanges 25 cooperating in retaining said rim on said flanges, and means connecting said disks.

20. In a disk wheel, a rim, an outer disk therein, an inner disk adapted to be shifted towards said outer disk and caused to clamp 30 said rim by portions of the outer disk being distended against said rim, and means for clamping said disks together with the rim thereon.

25. In a disk wheel, a rim, inner and outer disks having peripheral flanges both extending 35 in the same direction and affording a seat for said rim, and extensions of the flange of said outer disk abutting the periphery of said inner disk and spacing the 40 peripheral portions of said disks apart.

In testimony whereof I affix my signature.

HAROLD J. BRADT.
